MAGAZINE TOOL HANDLE

Peter F. Riggio, Woodside, N. Y.

Application July 24, 1946, Serial No. 685,996

5 Claims. (Cl. 145—62)

1

This invention relates to hand tools and more particularly to a hand tool adapted to have various implements detachably secured thereto and compactly carried thereby, which tool, with the said implements, being generally termed a combination tool.

Briefly described, the invention includes a tubular casing providing a housing for the various detachable implements and having an elongated cut-away portion intermediate its ends which is normally closed by a removable cover formed to complete the tubular wall, a fixed, axially bored plug which with a spring loaded plunger movable radially in the plug provides a chuck in one end of the casing, and a ring-shaped member rotatable on the plug and cut back from its inner edge to form a segmental portion overlying the outer end portion of the cover, an object of the invention being to employ this ring-shaped member by rotary movement as a common means for first locking the cover in position on the casing and then operating the chuck to grip an implement inserted therein.

Another object of this invention is to provide an improved hand tool which will be relatively inexpensive to manufacture, simple in construction, of a minimum number of parts, pleasing in appearance, compact, and very efficient and durable in use.

With these and other objects in view, which will appear as the description proceeds, there has been illustrated in the accompanying drawings a form in which the features and principles of this invention may be conveniently and practically embodied.

In the drawings:

Figure 1 is a side view of a hand tool embodying the features and principles of this invention;

Figure 2 is a side view of the hand tool with the attachment illustrated in Figure 1 removed, the cover being shown as unlocked.

Figure 3 is a top view of the right hand end of the tool seen in Figure 2 but with the cover securing ring rotated 90° with respect to the position in which it is seen in Figure 2.

Figure 4 is a detail perspective view of the cover.

Figure 5 is an enlarged cross-sectional view taken on the line 5—5 of Figure 1;

Figure 6 is a longitudinal sectional view taken on the line 6—6 of Figure 5;

Figure 7 is a sectional view similar to Figure 6 but looking in an opposite direction;

Figure 8 is a cross-sectional view similar to Figure 5 but with the parts in another position;

Figure 9 is a broken sectional view taken on the line 9—9 of Figure 8;

Figure 10 is a cross-sectional view taken on the line 10—10 of Figure 6;

Figure 11 is a cross-sectional view taken on the line 11—11 of Figure 6;

2

Figure 12 is a broken sectional view taken on the lines 12—12 of Figure 11;

Figure 13 is a cross-sectional view taken on the line 13—13 of Figure 6;

Figure 14 is an end view of the tool clamped handle and casing cover securing ring; and

Figure 15 is a side view of the said ring.

Referring now to the drawings wherein like reference numerals designate like parts throughout the several views, the numeral 11 denotes the tool handle in its entirety, and the numeral 12 denotes a device in its entirety which may be detachably secured to the handle 11. The handle 11 comprises a hollow cylindrical casing 13, having

a detachable cover 14, and a detachable hollow cylindrical end closing member 15. The cylindrical handle casing 13 is open at one end to be closed by the member 15 and is closed at its other end by an implement shank receiving

20 plug 16. The casing 13 is cut away the greater part of its length intermediate its ends parallel with its axis and the cover 14 is formed to cover this opening and to complete the cylindrical form. One end 17 of the casing 13 is one-

25 half cylindrical in form and embraces a reduced end 18 of the plug 16, being secured thereto by soldering or brazing. The other end 19 of the casing 13 is completely cylindrical in form and embraces a reduced end 21 of the cylindrical end

30 casing member 15.

The cover 14 has a reduced end portion, or lip, 22 adapted to slip under the end portion 19 of the casing 13. A ring 23, embracing the plug 16 and the casing end 17, is cut away at 24 to

35 allow the cover 14 to be disposed in position in the cutaway of the casing 13 and is rotatable about and upon the casing end 17 and plug 16 to dispose the remaining lip portion 25 of the ring 23 over the end of the cover 14. The combined

40 action of disposing the cover lip 22 under the casing end 19 and disposing the ring lip 25 about the end of the cover 14 will detachably and firmly

secure the cover 14 to the casing 13.

The ring 23 is provided with a slot 26 in its full diameter portion to receive a nubbin end 27 of a plunger 28 mounted for radial movement in a counterbore 29 in the plug 16. A spring 31 constantly urges the plunger 28 outwardly by reacting between a shoulder 32 on the plunger and

45 the bottom of the counterbore 29. The nubbin end 27 of the plunger 28 detachably secures the ring 23 on the plug 16 and casing end 17 and limits the rotative movement of said ring thereon in both directions by engaging the ring

50 at the ends 33 and 34 of the slot 26. The ring 23 also has a hole 35 provided therein spaced from the end 33 of the slot 26, to allow a screw threaded end 36 of a hammer implement 37 to pass therethrough and be screw threaded into a

55 threaded hole 38 formed in the plug 16, see Figure 5. The plug 16 is of metal and acts with the

implement 37 to provide a weighted end for the tool to facilitate use of the same as a hammer.

The plug 16 functioning as a chuck is provided with an axial hole 39 which is generally circular in cross-section and has a flattened portion 41. The hole 39 is adapted to receive the shanks 42 of the various implements which shanks are generally circular in cross-section and each having a flattened portion 43. The plunger 28 extends through the plug 16 into the hole 39 therein at the flattened portion 41 to have its end 44 engage against the flattened portion 43 on the shank 42, of the implement selected for use, to secure it to the handle 11. As some of the implements require attachment to the handle 15 against lengthwise movement relatively thereto, the shank 42 is also provided, at its flattened portion 43, with a cross groove 45 into which the plunger end 44 will seat.

The plunger 28 is pressed inwardly to cause its end 44 to clamp the implement shank 42 in the plug 16 by rotating the ring 23 on the plunger 28 to dispose the nubbin end 27, of the plunger 28, under the ring 23 in a shallow groove 46 formed in the internal peripheral surface of the ring beyond the slot end 34, see Figure 8. Rotating the ring 23 to dispose the nubbin end 27 beyond the end of the groove 46, see dotted lines in Figure 9, will press the plunger end 44 into the cross-slot 45 in the implement shank 42.

The arcuate portion 47 of the casing remaining after being cut away is provided with a multiple clip 48 formed from a strip of sheet metal by corrugating it to form loops 49, 51, and 52. The base portions of the loops 49, 51, and 52 are secured, as by soldering, or brazing, to the internal surface of the casing portion 47 and the outwardly extending arm portions of these loops are adapted to spring press against the sides of implements such as a tack puller 53, a pair of pliers 54, and a can opener 55, see Figures 6 and 10. The arcuate cover 14 is also provided with a clip 56 having a loop 57 in which the hammer shank 36 may be held. The ends of the clip 56 are secured to the internal surface of the cover 14 and the clip is tensioned to provide a portion 58 adapted to clampingly hold an implement such as a flat file 59 between it and the cover 14, see Figures 7 and 10. The outer peripheral surface of the cover 14 is provided with indicia in the form of a four-inch scale 61, see Figure 1, for use in laying out work, etc.

The casing end closing member 15 is detachably secured to the casing portion 13 by having the reduced end 21 thereof provided with diametrically opposite L-shaped slots 62 each arranged to receive a pin 63 secured to and extending inwardly from the cylindrical casing end 19, see Figures 11 and 12. One end of the L slot opens at the end of the member 15 to receive the pin 63 when the reduced end 21 of the member 15 is moved axially into the casing end 19 and the other portion of the L-slot extends peripherally along the reduced end 21 to lock it to the casing end 19 when the member 15 is rotated relatively to the casing.

The member 15 has a thickened end 64 at its outer end and from this end 64 a tube 65 axially extends to its open end. The thickened end 64 is provided with a concentric hole 66 to receive the reduced end of a flash-light bulb 67. The threaded metallic contact shell 68 of the bulb 67 has a coiled spring 69 threaded thereon which extends outwardly from the shell 68 to contactingly engage the end edge of the metallic shell 70

71 of a dry cell 72 disposed in the tube 65 and, by spring tension reacting between the cell 72 and the bulb 67, to normally maintain a bulb contact stud 73 and contact stud 74 of the cell 72 out of contact. A plug 75 is disposed in the outer end of the tube 65. The plug 75 has a nubbin 76 extending outwardly therefrom by which the cell 72 may be pressed against spring tension to cause the contact studs 73 and 74 to be engaged to energize and light the filament of the bulb 67.

Radiating from the tube 65 from its outer periphery to the inner periphery of the member 15 are a plurality of partitions 77 separating this space into compartments 78 into which various implements may be placed. For instance in one compartment is a chisel 79 and in another a gouge 81. A saw blade 82 and another implement 83 such as a brush is disposed in another of the compartments. Figure 13 shows the shank ends of these and other implements which may consist of drills, rat-tail file, reamers, etc., disposed in the compartments 78. A flat ring-shaped cover 84, having a broken-away portion 85 is disposed over the open end of the compartments 78 and encircles the outer end of the tube 65. The ring-shaped cover 84 may be retained in place by spinning the outer edge of the tube 65 over upon the outer surface of the cover 84. The cover 84 is arranged to resolve about the tube 65 to uncover any of the compartments 78 from which it is desired to remove an implement, after first removing the saw blade 82, which, when in place, serves to prevent the cover 84 from revolving to uncover the compartments.

The plug 75 is retained in the tube 65 by a ring 86 which encircles the nubbin 76. The ring 86 has a tab 87 extending radially therefrom over the ring-shaped cover 84 to be attached thereto by a screw 88. The ring 86 is spring tensioned and, when the nubbin 76 and plug are depressed to cause the contacts 73 and 74 to engage and energize the bulb filament, may be rotated on the screw 88 to overlie the nubbin 76 to hold the contacts 73 and 74 in engagement and the bulb lighted. The flashlight can only be actuated when the member 15 is detached from the casing portion 13, although after lighting the bulb the member 15 may be again attached to the casing for convenience in holding it.

The open slot 26 and the internal groove are in the axial plane of the plunger 28, the rounded outer end 27 of which always engages in one or the other and thus retains the ring member 23 against axial displacement. As the lip 25 disengages the cover 14 rotation of the ring in one direction is positively stopped by engagement of the end 33 of slot 26 with the nubbin 27. In order, however, to permit further rotation of the ring in the opposite direction, after engagement of the slot end 34 with the nubbin 27, the inner surface of the ring at the juncture of the groove 46 and slot 26 is slightly chamfered. This provides a slight cam surface which permits the rounded nubbin end of plunger 28 to ride under the ring into the groove 46 thus forcing the plunger 28 into operative position against action of the spring 31. The relative circumferential positioning of the lip portion 25 of ring member 23 and the slot 26 is such that the cover 14 is always secured against removal during movement in or out of the implement locking plunger 28.

The hand tool above described is particularly useful and practical, various implements always

being available for general repairs in the home, shop, automobile, or boat. Due to the novel arrangement of the implement holding means, all of the implements may be carried by the casing in a convenient manner and be readily available. The member 15 adapted for use as a flashlight and implement holder also forms an end closure means for the casing 13 and assists in retaining the cover 14 in place. The ring 23, while acting as cover 14 retaining means, is also adapted to clamp the various implements to the casing 13 in the plug 16 through the plunger 28 which, in turn, acts to retain the ring 23 in place by extending through the slot 26.

Due to the provision of the above described novel features, a particularly useful, practical, and efficient hand tool is provided.

While there has been shown and described herein one form of hand tool in which the features and principles of this invention may be embodied in practice, it is to be understood that the same may be embodied in other specific forms without departing from the spirit and essential attributes thereof, and it is therefore desired that the present embodiment be considered in all respects as illustrative and not restrictive, reference being had to the claims rather than to the foregoing description to indicate the scope of the invention.

Having thus fully described the invention, what is claimed as new and for which it is desired to secure Letters Patent, is:

1. In a hand tool, a tubular casing having a cut-away portion intermediate its ends, a cover for the cut-away portion of said casing, a plug in one end of said casing, said cover having a lip extending from one end thereof adapted to slip under a portion of the casing at one end of the cut-away portion, a ring-shaped member rotatably mounted on said plug, said ring-shaped member having a lip extending from one end thereof to embrace the other end of said cover and lock it in position on the casing when said lip is disposed over said cover by rotation of said member on said plug, said plug having a hole therethrough to receive a tool shank, and means to clamp a tool shank in the hole in said plug.

2. In a hand tool, a tubular casing having a cut-away portion intermediate its ends, a plug in one end of said casing and having an axial opening therethrough to receive the shank of an implement, a cover for the cut-away portion of said casing, a spring pressed plunger extending radially through said plug and into the opening therein to engage an implement shank and lock it in place, the outer end of said plunger being rounded and normally protruding somewhat beyond the periphery of said plug, and a ring-shaped member rotatable on said plug to engage the outer rounded end of the plunger and depress the plunger to lock an implement in the opening in said plug, said ring-shaped member having a lip extending from one end thereof to embrace an end of said cover to secure the cover to the casing.

3. In a hand tool, a tubular casing having a cut-away portion intermediate its ends, a plug in one end of said casing, an opening through said plug to receive the shank end of an implement, a cover for the cut-away portion of said casing, a spring pressed plunger extending through said plug to engage and lock an implement shank end in the opening in the plug, said plunger having a nubbin extending outwardly

beyond the periphery of said plug, a ring-shaped member rotatable on said plug and adapted to engage on the outer end of said nubbin and depress said plunger into locking engagement with said implement shank end and a lip extending from one end of the ring-shaped member, said ring-shaped member having a peripheral slot formed part way around it and an inner peripheral groove one being continuous of the other and lying in the axial plane of said plunger to receive the said nubbin, one end of said slot providing a stop limiting rotation of said ring member in one direction, the other end of said slot being chamfered to permit entry of said nubbin into said groove, the said lip when in one position of rotation embracing said cover to secure it in position on said casing and when in another position of rotation permitting removal of the cover.

20 4. In a hand tool a tubular casing having a cut-away portion intermediate its ends, a cover for the cut-away portion of said casing, a plug in one end of said casing, said plug having a hole therethrough to receive the shank of a tool, 25 means to clamp a tool shank in the hole in said plug, and a ring-shaped member rotatable on said plug and having one end cut-away to form a lip adapted to overlie an end of said cover and secure it to said casing upon rotation of said ring member upon said plug.

5. In a hand tool a tubular casing having a cut-away portion intermediate its ends, a cover for the cut-away portion of said casing, a plug in one end of said casing, and a ring-shaped member rotatable on said plug and having one end cut away to form a lip adapted to overlie an end of said cover and secure it to said casing upon rotation of said ring member upon said plug, said plug having a threaded hole extending substantially radially thereto and said ring member having a hole therethrough adapted to be aligned with the threaded hole in said plug by rotation of the ring member on said plug to receive the threaded shank of an implement.
